TAPERING PANEL CONSTRUCTION FOR
FOUNDATION GARMENTSJoseph Leonard, Allentown, Pa., assignor to Mona
Lisa Foundations, Inc., a corporation of New
York

Application October 31, 1951, Serial No. 254,085

4 Claims. (Cl. 2—36)

1

My invention relates to improvements in foundation garments such as girdles, "all-in-one" garments and the like.

Specifically, I have found that extraordinarily effective control of the body contour is obtained when the foundation garment is constructed with a plurality of tapering elastic panels inset circumferentially and horizontally on either side of the garment. These elastic panels are formed with sides tapering symmetrically so that they become progressively narrower as they approach the front of the garment. The panels are made of elastic material which is stretchable only along the horizontal axis of each panel and these tapered panels are placed symmetrically on either side of the front of the garment so that their respective axes of elasticity are focused to meet adjacent the midpoint at the front of the garment.

In constructing my foundation garment I provide a fabric panel at the front center of the garment which is stretchable vertically but not horizontally. I provide a corresponding panel or panels at the back center of the garment which are likewise stretchable vertically or alternately vertically and horizontally. Elastic fabric panels stretching horizontally are attached on either side of the garment to the corresponding side edges of the top and bottom portions of the vertically stretchable front and back panels. The tapering elastic panels of my invention are inserted and attached on either side of the garment between the horizontally stretchable panels at the top and bottom and between the vertically stretchable panels on each side to form an integral foundation garment with the lines of elasticity of the tapering elastic panels focused toward the area immediately adjacent the midpoint at the front of the garment.

With this type of construction I have found that when the garment is adjusted on the body a plurality of tensions are set up within the foundation garment with the result that the narrowing portion of the tapering elastic panels tends to pull the abdomen in along lines which diverge at the same time that the widening portion of the same panel at the rear of the garment tends to pull the buttocks up along lines which tend to converge.

Preferably, I form the tapering panels with double layers of elastic fabric stretching solely along the horizontal axis of the panel. I use single layers of elastic fabric in other portions of the foundation garment. By using double layers in the tapered panels I obtain greater tension in the critical areas. Of course, instead of double layers I can provide for greater tension in these areas by having the elastic thread in these fabric panels made with substantially greater elastic tension.

In the drawing Fig. 1 is a front elevation and Fig. 2 is a rear elevation showing a foundation

2

garment embodying my invention in which the tapering elastic panels extend circumferentially around the garment from the back to the front separated by front and back vertically stretchable panels; Fig. 3 is a front elevation and Fig. 4 is a rear elevation of a different embodiment of my invention showing a foundation garment where the tapering elastic panels are inset at the front of the garment and do not extend as far back as the corresponding members in Fig. 1 and Fig. 2.

In the drawing the double arrows indicate the direction along which the material is stretchable.

The foundation garment 10 consists of front panel 12 which is stretchable vertically as indicated by the directional arrow in the drawing and the rear panel 14 is likewise stretchable vertically. The horizontally stretchable side panels 16 and 18 are shown at the top of the garment. Corresponding horizontally stretchable side panels 20 and 22 are shown at the bottom of the garment 10. The tapering elastic panels 24, 26 and 28 are shown at one side of the garment 10 and corresponding tapering panels 30, 32 and 34 are attached at the other side of the garment. Fig. 1 shows diagrammatically the axis of elasticity of each tapering panel tending to meet at the midpoint at the front of the garment. In Fig. 2 these same axes are shown tending to diverge at the rear of the garment.

The tapering elastic panels 24, 26, 28, and 30, 32 and 34 in Fig. 1 and Fig. 2 extend without interruption from the sides of the front center panel 12 to the sides of the back panel 14.

In the type of structure shown in Fig. 3 and Fig. 4 the tapering elastic panels 36, 38, 40, and 42, 44, and 46 do not extend entirely around to the back of the garment but are shorter and cover principally the front portion of the garment extending from the sides of the front center panel 48 to the sides of the hip or side panels 52 and 58.

The foundation garment shown in Fig. 3 and Fig. 4 contains a front panel 48 and a panel member 50 in the back. Vertically stretchable panel members 52 and 58 are shown in Fig. 4 together with horizontally stretchable side panels 54 and 56 on either side of back panel 50. In this construction the back and side panels are alternately stretchable horizontally and vertically.

Conventional zipper members are shown at 55 23 and 56.

The tapering panel members in my foundation garment may be attached to each other by fagoting along the seams, by zigzag stitching, or by a trimming seam or the like. In any case, these panel members should be joined together

without binding or restricting the stretchability of the panel members.

I have described and shown preferred embodiments of my invention but it is apparent that my invention need not be restricted to these specific embodiments and that changes in detail and in methods of assembly may be made without altering the basic structure of my invention.

What I claim is:

1. In a foundation garment having a plurality of fabric panels joined together circumferentially to form an integral garment the combination comprising: a front fabric panel, a back fabric panel, elastic fabric panels attached to side edges of the top and bottom portions of the front and back panels on each side of the garment, said elastic panels being stretchable horizontally but not vertically and being affixed to the garment so that tapered elastic panels may be interposed in the garment between the aforesaid top and bottom horizontally stretching fabric panels, a plurality of tapered elastic fabric panels joined together along their contiguous edges and attached at their free edges to the sides of the front and back panels and to inner edges of the horizontally stretchable elastic panels connecting the front and back panels, each such fabric panel being tapered symmetrically and being stretchable along a single line of elasticity and only in a direction along the axis of each such taper, such fabric panels being attached to the garment so that the axis of each fabric panel tends to meet the axes of the other tapered fabric panels at a point adjacent the front midpoint of the garment forming thereby a foundation garment capable of pulling the abdomen of the wearer in along diverging lines of uniform tension at the same time that the garment tends to pull the buttocks up along converging lines.

2. In a foundation garment having a plurality of fabric panels joined together circumferentially to form an integral garment the combination comprising: a front fabric panel, a back fabric panel, both panels being formed of elastic material stretchable in the garment vertically but not horizontally, elastic fabric panels attached to side edges of the top and bottom portions of the front and back panels on each side of the garment, said elastic panels being stretchable horizontally but not vertically and being affixed to the garment so that tapered elastic panels may be interposed in the garment between the aforesaid top and bottom horizontally stretching fabric panels, a plurality of tapered elastic fabric panels joined together and attached at their free edges to the sides of the front and back members and to inner edges of the horizontally stretchable elastic panels connecting the front and back panels, each such fabric panel being tapered symmetrically and being stretchable along a single line of elasticity and only in a direction along the axis of each such taper, such fabric panels being attached to the garment so that the axis of each fabric panel tends to meet the axes of the other tapered fabric panels at a point adjacent the front midpoint of the garment forming thereby a foundation garment capable of pulling the abdomen of the wearer in along diverging lines of uniform tension at the same time that the garment tends to pull the buttocks up along converging lines.

3. In a foundation garment having a plurality of fabric panels joined together circumferentially to form an integral garment the combination comprising: a front fabric panel, a back fabric panel, both panels being formed of elastic material stretchable in the garment vertically but not horizontally, elastic fabric panels attached to side edges of the top and bottom portions of the front and back panels on each side of the garment, said elastic panels being stretchable horizontally but not vertically and being affixed to the garment so that tapered elastic panels may be interposed in the garment between the aforesaid top and bottom horizontally stretching fabric panels, a plurality of tapered fabric panels joined together and attached at their free edges to the sides of the front and back panels and to inner edges of the horizontally stretchable elastic panels connecting the front and back panels, each such fabric panel being tapered symmetrically and being stretchable along a single line of elasticity and only in a direction along the axis of each such taper, such fabric panels being attached to the garment so that the tapering panels are placed symmetrically on each side of the front of the garment so that their respective axes of elasticity are focused to meet adjacent the midpoint at the front of the garment.

4. In a foundation garment having a plurality of fabric panels joined together circumferentially to form an integral garment, the combination comprising: a front fabric panel, side fabric panels on each side of the garment, a back fabric panel, elastic fabric panels attached to side edges of the top and bottom portions of the front and side panels on each side of the garment, said elastic panels being stretchable horizontally but not vertically and being affixed to the garment so that tapered elastic panels may be interposed in the garment between the said top and bottom horizontally stretching panels, a plurality of tapered elastic fabric panels joined together along their contiguous edges and attached at their free edges to the sides of the front and side panel members and to inner edges of the horizontally stretchable elastic panels connecting the front and side panels, each such fabric panel being tapered symmetrically and being stretchable along a single line of elasticity and only in a direction along the axis of each such taper, such fabric panels being attached to the garment so that the axis of each fabric panel tends to meet the axes of the other tapered fabric panels at a point adjacent the front midpoint of the garment forming thereby a foundation garment capable of pulling the abdomen of the wearer in along diverging lines of uniform tension.

JOSEPH LEONARD.
